APPARATUS FOR THE MOVEMENT OF
VISCOSUS MATERIALSJoseph M. Perignat, Forest Hills, N. Y., assignor
to General Tank Service, Inc., New York, N. Y.,
a corporation of New York

Application October 24, 1944, Serial No. 560,172

5 Claims. (Cl. 103—272)

The present invention relates to an apparatus and method for pumping viscous material such as tank sludge through a transmission line.

More particularly the invention relates to means for removing oil residues from the storage tanks of refineries. In such tanks, in the course of time, heavy and extremely viscous sludge deposits collect in such quantities that they seriously encroach upon the storage space of the tanks.

Steam ejector pumps have been used for removing sludge deposits such as those mentioned above. The present device, however, is a great improvement over the prior devices in that the nozzles thereof are adjustable with great ease and are so constructed as not to require the entire disassembling of the device. Furthermore, the present device is provided with two nozzles so arranged that it may be efficiently utilized with either one or both of the nozzles in operation and thus be effective in a variety of situations.

It is an object of my invention to provide a steam jet pump particularly for the movement of viscous liquids in which the steam nozzles are readily adjustable.

It is another object of my invention to provide such a jet pump so constructed that either a two nozzle device may be assembled from the parts or a single nozzle device may be assembled utilizing substantially the same parts omitting simply one of the nozzles.

Further objects and features of the invention will be apparent when the following description is considered in connection with the annexed drawing in which:

Figure 1 is a longitudinal cross section of the jet pump of my invention; and

Figure 2 is a fragmentary section showing the mode of adjusting the position of one of the nozzles. This section is taken on the plane of line 2—2 of Figure 1.

Referring now to the drawing, there is shown at 1 the pump body which comprises a relatively narrow throat portion, the enlarged discharge end 2 and the enlarged intake end 3.

The intake end 3 is generally conical in form as is indicated at 4 and is provided with a shoulder 5 in which an annular ring 6 is pressed, this ring being tapered to form together with the tapered end 7 of the nozzle piece 8 an annular steam jet opening 9. The member 3 is also provided with an annular groove 10 which forms a steam chamber and through which the opening 11 permits the ingress of steam.

The nozzle piece 8 is threaded at its left hand end (as seen in Figure 1) and is provided with

keyways into which keys formed on the walls of the member 3 fit. The keys and keyways are not shown in the drawing.

The member 3 is also provided with a boss 12 (see Figure 2) which has a circular bore therein. Fastened to this boss by suitable means, as for example by the screws 13, is a bearing 14 which bearing rotatably supports a stub shaft 15 to one end which is affixed the worm 16 and to the other end of which a handwheel 17 is fastened.

By means of this construction rotation of the handwheel 17 is effective to rotate the worm 16 and therefore the cooperating wormwheel 18, which wormwheel, as may be seen in Figure 1, is threaded on its interior surface and mates with the threads on the member 3. The wormwheel is retained against longitudinal movement by means of the flanges 19 and 20, the flange 19 being integral with the member 4 and the flange 20 being formed upon the body piece 21 which body piece is similar to body piece 3. Thus, when the wormwheel 18 rotates the nozzle 8 is moved longitudinally with respect to the member 6 whereby the amount of steam issuing through the annular opening formed by the members 6 and 7 is adjusted.

As shown in Figure 1 a second nozzle is provided, this being similar to the parts just described so that the pumping action occurs in two stages.

At the rear or left hand of the instrument as shown in Figure 1 a flange ring 22 is provided and is screwed to the member this ring being provided with internal threads into which a threaded intake pipe such as 23 may be inserted.

The nozzle of this stage may be exactly similar to and adjusted in a manner identical with that already described above in connection with the second stage of the pump. If desirable, the pump may be a single stage one only in which case member 21 will be omitted and replaced by a ring similar to ring 22 but designed to fit on the flange of member 3 rather than on member 21. This ring would be internally threaded as is ring 22 for the insertion of a pipe such as 23 and with this construction a single stage jet pump is provided.

When two jets are used as shown in Figure 1 the inner nozzle, that is the one designated 8, acts mainly as a pressure discharge nozzle while the outer nozzle acts solely as a vacuum intake nozzle.

The above description has been given for purposes of description only and it is to be understood as not limiting the invention to the apparatus shown and described. It is clear that modifications and alterations may be made without departing from the scope of my invention and

therefore I wish to be limited solely by the appended claims.

What is claimed is:

1. A steam jet pump comprising, in combination, a narrow throat portion, an enlarged intake portion, an annular nozzle ring in said intake portion, a nozzle piece in said intake portion cooperating with said ring and means for adjusting said nozzle piece with respect to said ring, said means comprising an internally threaded wormwheel mounted on threads of said nozzle piece and restricted against longitudinal movement, a worm mounted to engage said wormwheel and means for manually rotating said worm to adjust said nozzle piece longitudinally of said annular ring.

2. A steam jet pump comprising, in combination, a narrow throat portion, an enlarged intake portion, an annular nozzle ring in said intake portion, a nozzle piece in said intake portion cooperating with said ring and means for adjusting said nozzle piece with respect to said ring, said means comprising an internally threaded wormwheel mounted on threads of said nozzle piece and restricted against longitudinal movement, a worm mounted to engage said wormwheel and means for manually rotating said worm to adjust said nozzle piece, said enlarged intake portion being provided with means to prevent rotative movement of said nozzle piece relative to said intake portion.

3. In a steam jet pump, in combination, a narrow throat portion, a plurality of enlarged intake portions arranged serially, an annular nozzle ring in each intake portion, an annular generally conical nozzle piece in each intake portion, each nozzle piece being adapted to move longitudinally with respect to its nozzle ring to vary the annular steam passageway therebetween, and means for adjusting each nozzle piece with respect to its cooperating intake portion and nozzle ring, said means comprising an internally, spirally threaded wormwheel mounted on each nozzle piece for rotative movement with respect thereto and a manually rotatable worm mounted in cooperative engagement with said wormwheel.

4. In a steam jet pump, in combination, a narrow throat portion, a plurality of enlarged intake portions arranged serially, an annular nozzle ring in each intake portion, an annular generally conical nozzle piece in each intake portion, each nozzle piece being adapted to move longitudinally with respect to its nozzle ring to vary the annular steam passageway therebetween and means for adjusting each nozzle piece with respect to its co-

operating intake portion and nozzle ring, said means comprising a helically threaded portion on said nozzle piece, an internally, helically threaded wormwheel mounted on said threaded portion, a boss on said enlarged intake portion, a bushing in said boss, a shaft mounted in said bushing and carrying a worm in engagement with said wormwheel and a manually operable handwheel for rotating said worm and thereby adjusting the position of the associated nozzle piece with respect to its ring.

5. In a steam jet pump, in combination, a narrow throat portion, an enlarged intake portion, an annular nozzle ring fixed in one end of said intake portion, an interior cylindrical surface formed at the other end of said intake portion, a nozzle piece adapted to move longitudinally toward and away from said nozzle ring and guided by said interior cylindrical surface, a helically threaded portion formed on said nozzle piece, a wormwheel having an internally helically threaded portion, said wheel being mounted on said nozzle piece with said threads in engagement, means on said intake portion for preventing longitudinal movement of said wormwheel in one direction, a boss on said intake portion, a shaft mounted in said boss, a worm mounted on said shaft in engagement with said wormwheel, manually operable means for rotating said shaft, and an annular flanged ring mounted on said intake portion, said ring having an annular flange projecting against said wormwheel and preventing longitudinal movement thereof in the opposite direction, said ring also being internally threaded for connection of an intake pipe thereto.

JOSEPH M. PERIGNAT.
